CORNER UNIT FOR A BASEBOARD RADIATOR

George W. Walker, Bloomfield Hills, Mich., assignor to
United States Radiator Corporation, Detroit, Mich., a
corporation of New York

Application December 22, 1953, Serial No. 28,175

Term of patent 14 years

(Cl. D81—21)

To all whom it may concern:

Be it known that I, George W. Walker, a citizen of the United States, residing at Bloomfield Hills, in the county of Oakland and State of Michigan, have invented a new, original, and ornamental Design for a Corner Unit for Baseboard Radiator, of which the following is a specification, reference being had to the accompanying drawings, forming a part thereof.

Figure 1 is a front perspective of a corner unit for baseboard radiator embodying my new design.

Figure 2 is a top plan view of Figure 1; and
Figure 3 is a side elevational view thereof only one side
being shown as the other side is identical.

I claim:

The ornamental design for a corner unit for a baseboard radiator, as shown and described.

No references cited.
